Attorney.

United States Patent Office.

WILLIAM RILEY, OF MADISON COUNTY, MISSISSIPPI.

Letters Patent No. 101,511, dated April 5, 1870.

IMPROVED WASHING-MACHINE.

The Schedule referred to in these Letters Patent and making part of the same.

To all whom it may concern:

Be it known that I, WILLIAM RILEY, of the county of Madison and State of Mississippi, have invented certain new and useful Improvements in Washing-Machines; and I do hereby declare that the following is a full, clear, and exact description of the same, reference being had to the accompanying drawing and to the letters of reference marked thereon, making part of this specification, in which—

Figure 1 is a side view.

Figure 2 is a horizontal sectional view.

Figure 3 is a top view.

The nature of my invention consists in securing the lower rubber of the washing-machine in a sash which has its bearings in a suitable sash-frame secured in the opposite sides of a rectangular box. The sash is supported by plate springs, which are provided with adjustable bearings. The upper rubber is connected with and worked by a rock-shaft, which receives its motion through suitable crank-gearing, as hereinafter described.

To enable others skilled in the art to make and use my invention, I will now proceed to describe its construction and operation.

A is an open frame-work, in which is secured the entire mechanism.

B is the box that contains the water, and is constructed in the usual manner. This box may be of any desired form and dimensions, but I usually make it rectangular, and about two and a half by four and a half feet, and three feet deep.

On the opposite sides of this box B are secured slats b b, which form a frame for the sash C to work in.

C is a sash, and is nearly square, its width being a little less than the longest dimension of the box B, so as to receive and allow of its free movement in the sash-frame b b.

This sash C is supported by two horizontal plate-springs, C' C', the ends of which pass through mortises or slots c c, cut in the upper section of the sash.

These springs C' C' also pass through openings in an adjustable and movable shaft D, and are permanently secured to a shaft, D', which is secured and works in suitable bearings at the end of the frame A.

The shaft D can readily be moved in a horizontal direction, and is rendered adjustable vertically, by means of screws d d.

On the lower cross-piece of the sash-frame C is secured the lower or clothes-support rubber E.

This rubber consists of a series of small rollers or open slats, e e, and is held through the tension of the springs C' C', both in its normal condition and also while the machine is in motion, at a point a little below the horizontal line, in which moves the upper rubber E'.

F is a lever, which is pivoted in a suitable support, F', attached to the side of the box B.

This lever F passes through a slotted bearing-plate, f, on the side of the sash C, and by means of which the sash, and consequently the rubber E, can be depressed at pleasure.

G is a lever, that is secured to the upper rubber E'.

This lever works in short, upright standards or supports G' G'.

H is a rock-shaft, which is pivoted in suitable supports h h, attached to the lever G, and h' h' attached to the main or crank-shaft K.

The crank-shaft K runs across the frame, and is secured in suitable bearings on one of the vertical supports of the same.

To this crank-shaft K are secured suitable crank-levers L L', by means of which the necessary rotary motion is given to the shaft to work the entire operating mechanism of the machine.

Instead of the lever F operating at the side of the sash C, it may be so changed as to operate on its center.

The operation is as follows:

Water is placed in the box B. Through the lever F the rubber E is depressed, and the clothes, having been properly soaked and soaped, are placed thereon, when the pressure being removed from the lever F the sash C is instantly raised through the tension of the springs C' C', and the rubber E, with the clothes thereon, is brought in contact with the rubber E'. Movement is then imparted to the machine simply by working the lever L.

Having thus fully described my invention,

What I claim therein as new, and desire to secure by Letters Patent of the United States, is—

The sash C, springs C' C', adjustable shaft D, lever F, and rubbers E E', when the latter is worked as shown, the whole being so combined and arranged as to operate substantially as described.

WM. RILEY.
